MAGNETIC LOCK

William Felix Stroud, Humber Bay, Ontario,
Canada, assignor to Neptune Meters Limited,
Long Branch, Ontario, Canada

Application May 25, 1944, Serial No. 537,322

4 Claims. (Cl. 70—276)

This invention relates to improvements in locks of the type in which a member connected with the latch or bolt is secured by pins or tumblers and said tumblers are operated to release the locked member through magnetic attraction and the principal objects of this invention are to devise a construction of lock which will present a multiplicity of combinations of locking elements, any of which will be practically impossible to operate to release the lock without the proper key.

A further object is to devise a lock which will be extremely simple to operate so that the mere placing of the key in position will instantaneously release the lock.

The principal feature of the invention consists in the novel arrangement of a plurality of pins of magnetized steel within enclosed recesses in a block which are adapted to engage in locking contact with a member connected with the lock-operating mechanism to hold said locked mechanism inoperative, said pins being operated to release the lock-holding member by means of a key member containing a selected arrangement of iron or steel inserts to which the magnetized pins will be attracted when the key is placed in position against the block containing the closed orifices housing the magnetized pins, the iron or steel inserts registering with such pin recesses in selected groups to operate the required pins to free the locking-holding member.

A further important feature consists in the novel construction and arrangement of the magnetic pin-controlled member in its operative connection with the lock bar or spindle.

A still further feature of importance consists in the arrangement of a recessed cover extending over the block in which the magnetic locking pins are mounted to receive the key but to prevent unauthorized manipulation of the lock pins.

In the accompanying drawing

Figure 1 is a longitudinal vertical sectional view through a lock mechanism constructed in accordance with this invention shown applied to a door structure and illustrating the position of the parts when the door is unlocked.

Figure 2 is a horizontal sectional view taken through the line 2—2 of Figure 1.

Figure 3 is a cross sectional view taken on the line 3—3 of Figure 1.

Figure 4 is a part longitudinal vertical mid-sectional view of the pin-locking portion of the mechanism similar to Figure 1 showing the parts in the locked position.

Figure 5 is a longitudinal mid-sectional view

of a padlock constructed in accordance with this invention.

Figure 6 is a part plan sectional view taken on the line 6—6 of Figure 5.

Figure 7 is a view similar to Figure 6 showing the locking plate diverted in one direction to prevent the unlocking of the lock.

Figure 8 is a view similar to Figure 6 showing the locking plate diverted in a direction different to that illustrated in Figure 7.

Figure 9 is a perspective view of the lock spindle and locking plate.

In the pin type of lock where a plurality of divided pins are mounted in a rotatable barrel the location of the division of the pins is determined by the edge contours of a key inserted into the barrel. Such type of lock is reasonably safe against tampering but persons skilled with locks can open this type.

The immediate danger to unauthorized entry to a locked enclosure is through the loss of keys or the copying of same, and it is extremely desirable to provide a lock which is practically immune from improper entry and which is opened by a type of key which will be extremely difficult to duplicate and impossible to duplicate unless it be in the possession of the party desiring to do so for a considerable time, the key having no contours or visible conditions which may be duplicated.

In the accompanying drawing, in Figures 1 to 4 I have shown an adaptation of my invention to a door lock of the type used on motor cars. In this construction I provide a flanged body 1 of part cylindrical form, the flange of which is adapted to be secured to the door 2. The outward end of the body 1 is formed with a cylindrical recess 3 in which is mounted the cylindrical end 4 of a handle 5. The handle is secured upon the end of the lock spindle 6 which extends into a door and is connected with the usual latch mechanism, a rocker arm 7 being here shown secured to the spindle, and engaging a plate 8 mounted on the twin pins 9, to which the latch 10 is secured, the latch being held in its outward position by suitable compression springs 11 mounted on the pins 9.

The end of the lock spindle 6 is preferably journalled in a tubular bracket 12 secured to the inner door plate 13, and a coil compression spring 14 is housed in the bracket 12 and holds the spindle in a position with the rocker arm 7 engaging the latch operating plate 8. When the spindle is in this position the cylindrical end 4 of the handle is located adjacent to the outward

end of the recess 3, and the handle can be pushed inwardly so that the spindle compresses the spring 14 and the rocker arm 7 is moved out of contact with the plate 8 so that the handle can be turned freely without operating the latch.

A cylindrical extension 15, of lesser diameter than that of the portion 4, is arranged at the inner end of the handle head and extends into a cylindrical bore 16 in the member 1. The upward side of the member 1 is flattened to intersect the cylindrical bore 16 and provides a flat horizontal surface 17 upon which a flat plate 18 is slidably mounted. This plate engages the inward end of the cylindrical extension 15.

The plate 18 is provided on its underside and intermediate of its length with a pin 19 which extends into an annular groove 20 formed in the spindle 6, so that when the handle and spindle move longitudinally the plate 18 moves with it, sliding on the surface 17.

The upper surface of the plate 18 has formed therein a plurality of shallow circular recesses 21 which may be arranged in rows or in any predetermined pattern, or any predetermined number.

Arranged above the plate 18 is a block 22 which is provided with a plurality of cylindrical recesses 23 which are positioned to register with recessed in the plate 18. Loosely mounted within the recesses 23 in the block 22 are pins 24 of a highly magnetized metal. These pins rest upon the top surface of the plate 18 when the lock is unlocked. That is to say, when the locked parts are in a position so that on the turning of the handle the latch will be operated to open the door.

Upon the pressing in of the handle and the spindle 6 the block 18 is caused to slide in relation to the block 22 which is held stationary, and when the recesses 21 in the block 18 move into register with the recesses 23 in the block 22, the magnetized pins drop into the recesses in the block 18, thus holding the handle in its inward position and the spindle in position so that the latch-operating rocker arm is disengaged from the latch mechanism. The latch thus remains locked.

One or more of the recesses in the surface of the block 18 are deeper than the others and a short pin 18', of magnet material is housed in the deep recess with its top end level with the top of the block so that the block may move freely in the sliding operation of the handle and one of the magnetized pins may move into alignment therewith, concurrently with the block 18 being moved to bring its recesses into register with the recesses 23 to lock the block 18.

If, when the block 18 is in this position, an attempt is made to open the lock by the use of a piece of iron or steel or a spurious key, the pin 18' will be lifted with the pins 24 and will intercept the movement of the block 18 and thus prevent the operation of the lock.

Mounted over the block 22 is a cover member 25 which is suitably secured to the member 1, and the top of the cover is spaced from the top of the block 22.

A recess 26 is thus provided into which a flat key member 27 is to be inserted. This key member is made of a non-magnetizable material and has mounted therein in suitably selected places, which will register with recesses 23 in the block 22, blocks 27' of iron or steel which will form a magnetic attraction for the pins 19 which may be arranged immediately therebelow.

When the key, provided with the required arrangement of metal inserts 27', is inserted into the recess 26 the pins, which it is desired to lift out of the recesses 21 of the block 18, will, through their magnetic attraction, lift upward toward the inserts in the key, thus freeing the block 18 from the pins which have been holding it in the locked position, and the spring 11 then forces the spindle outwardly, moving the plate 18 so that the surface recesses 21 therein move out of register with the magnetic pin recesses.

It will be understood that the recesses 23 in the block 22 do not extend through to the top of the block but a thin wall of the material of which the block is formed is interposed between the pin and the key, but this does not interfere with the transference of the magnetic flux.

The arrangement of the cover 25 extending over the top but spaced from the block 22 prevents persons attempting to tamper with the lock from placing metal bodies in contact with the block 22, and the air gap formed by the key recess is such as to completely break the magnetic flux if an attempt is made outside the cover.

It will be readily understood that the arrangement of the number of pins in the block 22 and the pattern of same may be arranged in a very extensive variation of combinations, so that a very extensive variety of combinations may be had without duplication. The sizes and spacing of pins may be varied as also may the width and length of the key slot and the key.

The principle of the lock structure herein shown and described may be applied to a great variety of locks for various purposes. The structure of the lock is simple. The pins can be of uniform length or their length can be varied and staggered to meet various requirements of variety.

In the form of the invention illustrated in Figures 6 to 9 which illustrates the adaptation of the invention to padlock form, the body 28 of the padlock is substantially rectangular in form and is provided with a rectangular recess 29 intermediate of its width.

One of the side walls is bored longitudinally to receive the long arm 30 of the U-shaped hasp or bolt 31 of the lock and a short bore 32 in the opposite side wall receives the free end of the hasp.

An annular groove 33 in the hasp arm 30 is engaged by a tongue 34 which forms part of a rectangular block 35 slidably arranged in the recess 29 and extending through a slot 36.

Pivoted on the upper face of the block 35 on a pivot 37 arranged near the bottom of the block, is a plate 38. This plate is round at the corners and is provided with a triangular shaped tongue 39 extending from the edge opposite site to the pivot.

Within the flat cross bar 40 of the lock body and facing inwardly is a central vertical V-shaped groove 41 into which the tongue 39 is adapted to enter, and a pair of angularly arranged notches 42 are arranged either side of the central groove. These engage the tongue 39 when the plate is swung to either side of the centre line on its pivot on the block 35.

Arranged in the top surface of the plate 38, preferably about the middle thereof, is a right angular triangular recess 43 which extends only a portion of the thickness of the plate. In other words, it is a shallow recess, and one of the walls

of said recess is parallel with the adjacent side edge of the plate.

The plate is also shown with a pair of angularly disposed recesses 44 and 45 arranged diagonally either side of the centre recess 43.

A block 46, which is fitted into the rectangular opening or recess 29 in the body of the padlock, has formed therein a plurality of cylindrical recesses 47 which are adapted to register with the recesses 43, 44 and 45 respectively, and within the recesses 47 are arranged highly magnetized pins 48 which will drop into the recesses 43, 44 and 45 in the pivotal plate 38.

The cover 49 is provided with a key slot 50 in the underside, into which a key, formed of non-magnetic material but having iron or steel plugs inset thereto arranged opposite to certain of the recesses 47, is inserted, so that upon the insertion of the key certain of the locking pins may be lifted out and others left in position.

In order that the lock may be opened the key must, in magnetic co-operation with the locking pins, lift the pins out of the recesses 44 and 45, while the pin engaging the recess 43 remains down. By pulling out upon the hasp the long arm, which engages the tongue 34 of the block 35 which carries the plate 38, moves outwardly, and as the pin in the recess 43 is engaging the top corner of this recess the plate will move outwardly with the block and the tongue 39 will enter the V-groove 41, thus allowing the block to move out far enough to allow the short end of the hasp to clear the holding recess when the hasp may then be swung on its pivot.

If however, a person attempting to open the lock without the proper key, pulls outwardly on the hasp it moves the block 35 and immediately upon the movement of the block 35 the pins, engaging the angularly disposed side walls of the recess 43 and the recesses 44 and 45, cause the plate to swing laterally, and the tongue 39 will be engaged by one of the lateral notches and hold the block from moving far enough to permit the hasp to clear the recess in the body.

If a plain piece of metal is inserted into the key slot and all the pins are raised and the hasp is pulled, the plate will swing on its pivot so that the tongue engages the notches at the other side of the centre groove 41. This is effected by means of a spring 51 secured in the cross bar of the body which engages the rounded corner of the plate 38 and holds it snugly against the pins.

It will be understood that a great variety of patterned arrangements of pin recesses can be arranged in the swinging plate 38 with corresponding arrangements of metal inserts in the key which will operate the pins properly to permit the unlocking of the hasp.

It will be understood that this arrangement of pivotal plate with recesses engaged by locking magnetic pins can be applied to a straight sliding bolt if desired.

A lock constructed according to the general principles herein disclosed can be varied to a considerable extent in detail construction without

departing from the principal feature of locking by means of magnetized pins to be moved out of locking engagement by placing a key having metal inserts to attract the magnetized pins in any desired pattern.

What I claim as my invention is:

1. In a magnetic lock, the combination with a locking member, of a slideable and rotatable spindle adapted to be operated with a sliding movement into and out of operating relation with said locking member, a block slideably mounted and rotatably connected with said spindle and having a plurality of selectively arranged recesses in one face thereof, a fixed block having cylindrical recesses selectively arranged to register with recesses in said slideable block, magnetized pins slideably mounted in the recesses in said fixed block and adapted to extend therefrom into the recesses in said slideable block to hold the spindle rotatably connected therewith out of operating engagement with the locking member, and a key having magnetic metal inserts to register with certain of said pin recesses and to operate said pins to release the slideable block and permit the slideable movement of the lock operating spindle.

2. In a magnetic lock, the combination with a body and a slideable lock bolt, of a block slideably mounted in said body and rotatably connected to said bolt, a member pivotally mounted on said block and having a projecting tongue and a plurality of surface recesses, a recess in said body adapted to receive said tongue upon the sliding of the block, magnetized pins slideably mounted in said body to extend into the recesses in said pivotal member to control the swinging movement of said pivotal member, recesses arranged on either side of said tongue-receiving recess of a lesser depth than same and adapted to restrict the sliding movement of said block carrying the pivotal member and prevent the freeing of the lock bolt, and a key of non-magnetic material having inserts of magnetic material arranged to control said magnetized pins to permit the unlocking of the lock bolt.

3. A lock as claimed in claim 2 in which the pivotal member is formed with diagonally arranged recesses and a triangular recess arranged therebetween to receive the ends of the magnetized pins to control the movement of the block connected to the lock bolt.

4. In a magnetic lock, the combination with a lock-operating mechanism, of a slideable member connected with the lock-operating member and having surface recesses selectively arranged and opening outwardly, a fixed block having recesses coinciding with the recesses in the slideable block and opening inwardly, a cover spaced from the outer side of said fixed block and forming a key recess and magnetic gap over said block, magnetized pins slideable in said block recesses, and a key member of non-magnetic material having inserts of magnetic material selectively arranged to attract selected magnetized pins to release said slideable member.

WILLIAM FELIX STROUD.
